UNITED STATES PATENT OFFICE.

PAUL LEON PRICE, OF MOUNT VERNON, NEW YORK, ASSIGNOR TO IRVING IRON WORKS COMPANY, OF LONG ISLAND CITY, NEW YORK, A CORPORATION OF NEW YORK.

DESIGN FOR A FLOOR GRATING.

Application filed January 9, 1922. Serial No. 120. Term of patent 14 years.

To all whom it may concern:

Be it known that I, PAUL LEON PRICE, a citizen of the United States of America, residing at Mount Vernon, in the county of Westchester and State of New York, have invented a new, original, and ornamental Design for Floor Gratings, of which the following is a specification, reference being

had to the accompanying drawing, forming part thereof.

The figure is a plan view of a grating, showing my new design.

I claim:

The ornamental design for a floor grating, as shown.

PAUL LEON PRICE.
